United States Patent Office

Des. 181,374

Patented Nov. 5, 1957

181,374

DISPLAY CABINET, OR SIMILAR ARTICLE

Bertram S. Silver, New York, N. Y.

Application July 20, 1956, Serial No. 42,316

Term of patent 7 years

(Cl. D80—9)

Figure 1 is a front elevational view of a display cabinet, or similar article, showing my new design;

Figure 2 is a view on the line 2—2 of Figure 1; and
Figure 3 is a vertical section on the line 3—3 of Figure 2 showing one rotatable unit in cross-section.

I claim:

The ornamental design for a display cabinet, or similar article, as shown.
